UNITED STATES PATENT OFFICE.

JOSEPH H. BOHAN, OF CHICAGO, ILLINOIS.

BINDING-CLIP FOR SHEET-MUSIC AND THE LIKE.

1,291,382.

Specification of Letters Patent. Patented Jan. 14, 1919.

Application filed October 8, 1917. Serial No. 195,306.

To all whom it may concern:

Be it known that I, JOSEPH H. BOHAN, a citizen of the United States, and a resident of Chicago, in the county of Cook and State 5 of Illinois, have invented certain new and useful Improvements in Binding-Clips for Sheet-Music and the like; and I do hereby declare that the following is a full, clear, and exact description thereof, reference being 10 had to the accompanying drawings, and to the characters of reference marked thereon, which form a part of this specification.

This invention relates to a novel binding 15 clip for binding or securing together at the fold line the edges of folded sheets, such as the leaves of sheet music, and the object of the invention is to provide a simple and inexpensive means to secure together the sheets at their turning edges so as to prevent 20 sheets which are normally loosely nested together from falling apart.

A binding clip embodying the present invention is especially useful for securing together the leaves of sheet music and like 25 folded sheets, but may be employed for other uses, as, for instance, for the purpose of securing or binding in place a sheet which may become detached from an ordinary bound book.

30 It is a common practice in assembling the sheets of sheet music, comprising more than two pages, to loosely nest the intermediate sheets between the first and last sheets, the first and last sheets constituting the cover. 35 In use these detachable sheets are liable to become misplaced, with the result that considerable time and annoyance is occasioned in finding the missing sheet and inserting it in its proper place, or if the sheet be lost 40 the remaining sheets are valueless.

In accordance with the present invention it is proposed to apply a strip or strips of flexible material to the outer cover sheets and to the inner loose sheets, in a form which 45 may be termed as a clip, said strip or strips being pasted to both the cover sheets and to the inner loose sheet or sheets at the fold thereof so as to constitute in themselves a hinged connection between the cover sheets 50 and the loose sheet or sheets, and also a means to prevent detachment of the loose sheet or sheets from the cover sheets. These clips are made of any suitable durable tough material, a fabric such as linen being preferable. The clips may be sold to users of 55 music so that the loose sheet or sheets of

sheet music may by the user be attached to the cover sheets, or the clips may be employed by the sheet music producer to thus attach the inner sheet or sheets to the outer 60 or cover sheets.

The invention consists in the matters hereinafter set forth and is more particularly pointed out in the claims.

In the drawings:—

65 Figure 1 is a plan view of a binding clip embodying my invention.

Fig. 2 is a plan view as seen from the reverse side thereof.

Fig. 3 is a perspective view of the clip 70 when folded.

Fig. 4 indicates the manner of using the clip in connection with a series of interleaved folded sheets.

Fig. 5 is a plan view of the hinge 75 edge of the assemblage of sheets.

A binding clip embodying the present invention comprises two end portions 10, 10 and an intermediate connecting portion or neck 11. The said clip is made of flexible, 80 pliable material such as binding cloth or linen. The end portions 10 are preferably of greater width than the connecting or neck portion 11.

To the corresponding sides of the end 85 portions 10 are applied patches 12 of paste, the pasted areas being preferably co-extensive with the areas of said enlarged ends or heads 10. Applied to the connecting portion or neck 11, on the side thereof opposite 90 to the paste patches or areas 12, is a third paste area or patch which is preferably co-extensive with said connecting portion.

Fig. 4 illustrates the manner of using the 95 binding clip. In said figure 15, 15 designate the outer or cover leaves or sheets and 16, 16 and 17 designate the inner leaves or sheets of an assemblage of sheet music. Said inner leaves or sheets are commonly interleaved loosely between the cover sheets 100 or leaves and, in accordance with a common practice, the inner leaves are an odd number, in which event the central leaf or sheet 17 is a single leaf or sheet while the others 16 usually comprise the two parts of a wider 105 sheet that is folded upon itself along its median line. In using the clip it is folded along the folding line indicated by 18 in Figs. 1 and 2, and as shown in Fig. 3, in a manner to bring the paste areas or patches 12 toward each other. These paste areas or patches are moistened and are pasted to the

middle sheet or leaf 17, one at each side thereof, leaving the folded connecting portion or neck 11 extending laterally away from the central sheet in its plane. The 5 cover sheets, and intermediate sheets 16 if the latter be present, are cut to provide narrow slits outwardly through which the extended folded connecting portions or necks of the clips are inserted. After the folded 10 necks have thus been inserted through said slits, or before if desired, the said folded connecting portions or necks are cut or parted along the fold line 18, and thereafter the separate neck portions are folded 15 laterally away from each other toward and against the outer faces of the cover sheets and are pasted thereto.

If desired a narrow binding strip 19 made 20 of a suitable tough fabric, as binder's linen, may be applied over the hinge edge of the assemblage of sheets so as to conceal the neck portions of the clips, to give a finish to the hinge edge of the sheets, and also to strengthen the connection between 25 the several interleaved sheets.

The clips, being thin, do not perceptibly increase the thickness of the hinge edge of the assemblage of sheets. Said clips constitute a very strong connection between the 30 sheets and prevent detachment of the normally loose sheets from the cover sheets and loss of such normally loose or inner sheets. The connection is an exceedingly simple,

economical one and employs but little paste in its application to the sheets.

I claim as my invention:—

1. Means to bind a folded cover sheet and an inner interleaved sheet comprising a strip, the end portions of which are adapted to be pasted to the opposite faces of the inner sheet at its edge, and with its intermediate folded portion adapted to be transversely folded and to extend through a slit in the fold of the cover sheet, whereby the folded portion may be divided and its members 40 may be folded back on the outer faces of the cover sheet at its fold and pasted thereto.

2. A binding strip for the purpose set forth comprising a continuous piece of fabric formed to provide at its ends enlarged 45 heads connected by a narrower neck portion, adapted to be folded along a transverse median line, said heads provided at one side of the strip with paste patches and the neck portion provided on the other side of 50 the strip with a paste patch.

In witness whereof I claim the foregoing as my invention I hereunto append my signature, in the presence of two witnesses, at Chicago, Illinois, this 3rd day of October, 60 1917.

JOSEPH H. BOHAN.
